UNITED STATES PATENT OFFICE.

HANS H. GOSCH, OF RANDALL, MINNESOTA.

ROAD DRAG.

Application filed August 25, 1921. Serial No. 495,152.

To all whom it may concern:

Be it known that I, HANS H. GOSCH, a citizen of the United States, residing at Randall, in the county of Morrison and 5 State of Minnesota, have invented certain new and useful Improvements in Road Drags; and I do hereby declare the following to be a full, clear, and exact description of the invention, such as will enable others 10 skilled in the art to which it appertains to make and use the same.

This invention relates to a road drag or scraper.

One important object is to generally 15 prove the construction of a machine of this type and particularly that set forth in Letters Patent of the United States #1,373,236 granted to me on March 25th, 1921.

Among the salient objects may be mentioned 20 the provision of such a machine having a novel lifting or elevating mechanism for the drag or surface-engaging means; one in which the scrapers and drag bar may have vertical yielding movement upon 25 encountering an obstruction; one having means to prevent undue lateral movement of the drag means and one having novel adjustable and reversible scraper blades.

Additional objects and advantages will 30 become apparent from the description hereinafter following taken in connection with accompanying drawings of one practical embodiment.

In said drawings:—

35 Figure 1 is a side elevation of the improved machine;

Figure 2 is a plan view thereof;

Figure 3 is a plan view of the drag means detached from the machine;

40 Figure 4 is a cross-section on line 4—4 of Figure 2;

Figure 5 is a cross-section on line 5—5 of Figure 2, and

45 Figure 6 is a detail cross-section on line 6—6 of Figure 2.

Throughout the different views like characters of reference designate like or corresponding parts. A conventional wheeled structure of the type usually drawn by two 50 or four horses, illustrates the application of the invention and may have a frame A provided with parallel side beams or bars 10. Rear wheels 11 are mounted on an axle 12 suitably journaled on the frame. Front 55 wheels 13 are journaled on an axle 14 carried by a draft or hitching structure 15

swiveled for lateral movement on a ball 16 on frame A by means of a socket 17. This ball and socket connection enables vertical tilting of the front wheels relatively to 60 frame A when encountering an obstruction. The driver's seat is shown at 18. Foot rests may be provided on beams 10 at 18^a.

Below and parallel with side beams 10 and the road are lifting bars 19 from which 65 drag means are suspended which in this instance comprise a drag bar or scraper blade B and a drag or plow scraper structure C. A flexible element 20 such as a chain is fastened at opposite ends as by 70 rings 21 to each bar 19. Intermediate its ends, each chain is secured to a lever 22 pivoted at 23 to the adjacent side beam 10, and having a plunger mechanism 24 cooperating with a quadrant 25 on such beam 75 to lock the lever in adjusted position. A pulley 26 is journaled on a stub shaft 27 on each beam 10 in the rear of the adjacent lever 22 while pulleys 28 and 29 are mounted on a stub shaft 30 projecting from 80 each beam. Guard plates are secured to beams 10 over the different sprocket chains employed. A supplemental guard plate is fastened to each guard plate 31, and extends across pulley 29. Said chains 20, starting 85 at their front ends, from lifting bars 19 pass over pulleys 29, are then connected to levers 22, then pass over pulleys 28 and 26 and are then fastened at their rear ends to the lifting bars. As a result of this construction, 90 levers 22 may be swung by the driver while seated to cause the chains 20 to raise and lower the lifting bars and the drag means supported thereby in a plane always horizontal and thus parallel with the 95 road and with said beams 10. Chains 20 may also pass over suitably positioned idler pulleys 20^a to avoid interference with levers 22.

Suspended from the lifting bars 19 as by 100 means of chains or flexible elements 32 are supporting bars 33 connected by horizontal pivots 34 to supporting bars 35 suspended by flexible elements or chains 36 from bars 19. Scraper blade B is elongated and angularly disposed, having a reinforcing rib 37. Brackets 38 depend from bars 33 and are secured to said rib 37 to support said blade B. Struts 39 connect and brace said bars 33.

110 Structure C has a main beam 40 rigidly secured to said supporting bars 35. Paral-

lel with beam 40 is a beam 41 having brackets 42 provided with angularly disposed slots 43 into which pins 44 on brackets 42 depend. Holders 45, in the form of angle 5 irons have one flange pivoted at 46 and 47 to said beams 40 and 41 to swing laterally. The vertical flanges of the holders have plow or scraper blades 48 removably and reversibly bolted thereto at 49. The forward 10 and rear edges of blades 48 are sharpened and in fastened position these blades depend below the holders 45. In due course the blades wear even with the holders at which time they may be reversed to present 15 the other sharpened edge for use.

Beam 41 is adapted for movement longitudinally relatively to and toward beam 40 to swing the holders 45 and blades 48 to different angles, such movement being permissible 20 due to the provision of said slots 43 and pins 44. To this end, a lever 50 is pivoted on beam 41 at 51 and swings relatively to a segment or other means 52 to which it may be fastened in adjusted positions. Pivoted to said lever 50 at 53 is a link or draw member 54 pivoted at 55 to the beam 40.

Secured as to the front of frame A are draft chains 56 which are fastened to supporting bars 55 and which may be upheld so 30 as not to interfere with operation of the front wheels and adjacent parts by means of a chain 57 spanning side beams 10.

In order that the drag means may not unduly move laterally relatively to the 35 frame A, one of the lifting bars 19 is disposed in openings 58 of brackets 59 supported by rods 60 which swing vertically in bearings 61 on beams 10. Struts 62 reinforce the brackets. Chains 62 and 63 extend from the brackets 59 to the beams 40 and 41 most remote therefrom, respectively.

It will be realized that the height of the drag means is controlled by the adjustment of levers 22 which through the medium of 45 chains 20 raise and lower the same, always maintaining same parallel with the ground.

The angle of blades 48 may be adjusted as desired by manipulating lever 50. Should the blades 48 strike an obstruction it will usually pass between adjacent blades but if 50 it be too large to do so, the structure C as a whole may yield vertically on pivots 34. Should blade B encounter an obstacle it may yield vertically independently of blades 48 and structure C as a whole, on said pivots 34. 55

Changes within the spirit and scope may be resorted to.

What is claimed is:—

1. A machine of the class described having a lifting bar, a supporting beam flexibly suspended from the bar, a second supporting beam flexibly suspended from the bar, means permitting relative movement of said bars on a horizontal axis transverse to the machine, and independent drag means supported from said bars. 60

2. A machine of the class described having pivoted brackets, a lifting bar mounted in said brackets, means to raise and lower said lifting bar, supporting members pivoted together and suspended from the lifting bar, chains extending from said brackets to the remote supporting members, and drag means carried by said supporting members. 70

3. A road scraper having a beam, a second beam, said beams being spaced apart, blades pivoted to said beams, a lever pivoted to one of said beams, a link means pivoted to said lever and to the other of said beams, 80 one of said beams being provided with angularly disposed slots, supporting members rigid with the other beam and projections on said supporting members entering said slots. 85

In testimony whereof I affix my signature in presence of two witnesses.

HANS H. GOSCH.
